UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed April 17, 1920. Serial No. 374,596.

To all whom it may concern:

Be it known that I, JOHN H. BELL, a citizen of the United States, residing at South Orange, in the county of Essex and

5 State of New Jersey, have invented certain new and useful Improvements in Signaling Systems, of which the following is a full, clear, concise, and exact description.

10 This invention relates to selective signaling systems and has for its object the provision of an improved signaling system which is particularly applicable to printing telegraphy.

15 Where there are a large number of printers on a single circuit, such as is the case in systems employed for commercial telegraph work, the continuous operation of the printer mechanism when the particular message is intended for but one station is, as is seen, very objectionable both from the standpoint of the wear of the printer parts and the unnecessary paper consumption. In order to obviate this condition the present invention provides a system 20 wherein the printer mechanism is normally disconnected from the line and the stations to which are assigned a particular combination of impulses may be signalled by the transmission of the impulses individual to the desired station for advising the attendant that the printer mechanism should be connected with the line.

25 In accordance with the object of the invention, there is provided a plurality of relays operating in response to a definite combination of impulses, to effect the operation of a signaling device upon the successive transmission of that combination to the called station, a definite number of times.

30 In attaining the object of the invention, there is provided at each of the several stations a plurality of relays arranged in conjunction with a distributor and responsive to the transmission of a particular combination of selecting units individual to each of the stations for causing the operation of an electromagnet which places a signaling device in condition for operation. The signaling device is thereby adapted to be operated due to the successive transmission of the particular combination of selecting units a predetermined number of times.

35 A better understanding of the invention may be had from the following description when taken in conjunction with the accom-

panying drawing, wherein there is shown only as much of the system as is necessary for a clear understanding of the invention.

Referring to the drawing, there is shown a line 2 incoming from a distant office (not shown), and to which there is serially connected a number of relays located at remote points. These relays are normally energized and have their contacts arranged to control the operation of a distributor and the application of a source of battery with a segmented ring of the distributor. The distributor 4, there being a similar distributor individual to each of the relays 3, has an arm 5, the rotation of which is controlled by a holding pawl 7. This holding pawl 7 is adapted to be withdrawn from engagement with the arm 5 upon the operation of an electromagnet 6, which is under the control of line relay 3 and is energized upon the deenergization of this relay. The arm 5 is provided with a brush 8 for completing a circuit between the different rings and segments of the distributor. A shaft 14 which has mounted thereon the arm 5, a cam 15 and a threaded member 26 are adapted to be rotated together as a unit. The arm 5 as well as the cam 15 is, however, only friction tight on this shaft and these parts are thereby only rotated when released due to the energization of magnet 6. There has been no means shown for rotating this shaft, but it is, of course, understood that some suitable means, such as a motor or the like, must be provided.

40 The distributor 4, as is shown in the drawing, is of the start-stop type and has a portion of the segments connected with the contact arms of a switch 13. The contact arms of this switch are so arranged in conjunction with the operating lever thereof as to be shifted simultaneously for disconnecting and connecting, depending upon the position of the switch, the selecting magnets of the printer mechanism shown in the 45 rectangle. This switch, when thrown so as to disconnect the selecting magnets, connects with the segments of the distributor, a group of relays such as 16 to 21 inclusive. These relays have their contacts so arranged that when a group of selecting units individual to the particular station at which these relays are located and which may be termed as a call signal, is transmitted over the line, they will be energized for 50

completing a circuit including the winding of a slow-release magnet 23. In order that the relays which are energized in accordance with the selecting units transmitted over the line may maintain their contacts closed during the time in which the distributor arm is completing its cycle, a locking circuit therefor is provided under the control of contact arm 22. This contact arm 22 is mounted in close proximity to the cam 15 and is operated thereby for closing its associate contact. The cam 15 has a portion of its surface recessed so that the locking circuit for these relays will be broken once per revolution of the cam 15 as the contact arm 22 is caused to disengage its associate contact when it rides in to the recessed portion of the cam. During the remainder of the cycle the locking circuit will, however, be maintained.

The energization of certain ones of the relays 16 to 21, due to the transmission of a particular combination of selecting units over the line causes the energization of magnet 23, there being a local circuit completed upon the energization of these relays including the winding of magnet 23. There is pivoted to one end of the armature of this magnet 23, an arm 24 having one end milled to fit the threads of the threaded member 26. The attraction of the armature of magnet 23, due to its energization, causes the arm 24 to engage the threaded member 26, and, inasmuch as the threaded member 26 is constantly revolving, the member 24 will be moved outwardly as long as magnet 23 is maintained energized and until the arm 24 has reached the end of the threads in the threaded member 26. This magnet is of the slow-release type, so as not to be released upon the momentary deenergization of the relays controlling its operation.

If the particular set of selecting units individual to the station at which relays 16 to 21 inclusive, are located, is transmitted over the line a definite number of times, the magnet 23 will be maintained energized and in consequence thereof the arm 24 will be caused to move outwardly through the action of the threaded member 26 to engage contact member 25. The number of times which the combination of selecting units must be transmitted over the line, will, of course, depend upon the distance intervening between the arm 24 and contact 25. The engagement of arm 24 with the contact member 25 closes a circuit including an alarm device, such as 27. This alarm device has been shown in the form of an ordinary bell, but it is, of course, obvious that any other suitable form of signaling device may be provided. It may also be desired to provide a locking circuit for the signaling device for maintaining it operated even after the several relays have released their arms.

tures, due to the cessation of the current impulses. This can, of course, easily be supplied by any one skilled in the art.

It is thought that a more definite understanding of the invention can be had from a description of the operation of the system as applied to a particular station. 70

A distant operator in desiring to call the attendant of the printer mechanism at station A would operate the transmitting apparatus so as to transmit the following set of selecting units: No current, current, no current, current, current, and no current. The transmission of such a set of selecting units causes the operation of all of the line relays and in consequence thereof the operation of the distributor at each of the stations. But inasmuch as a definite set of selecting units is assigned to each station for effecting the operation of relays 16 to 21 in a certain prescribed manner for causing the energization of the electromagnet 23, the signal device at only one of the stations will be operated, due to the transmission of the above set of selecting units. The operation of the distributor is effected due to the transmission of the first unit; that is, the removal of current from the line which causes the deenergization of line relay 3. The deenergization of this relay connects the battery 12 with the winding of magnet 6, and if the brush 8 of the distributor 4 is in contact with segments 9 and 10 thereof, an energizing circuit for magnet 6 is completed. This causes the distributor 4 to rotate, so that the brush 8 will be in contact with segments 11 and 12, which connects the battery 12 with the winding of magnet 14. The energization of magnet 14 causes the line relay 15 to operate, which connects the battery 12 with the winding of magnet 16. The energization of magnet 16 causes the line relay 17 to operate, which connects the battery 12 with the winding of magnet 18. The energization of magnet 18 causes the line relay 19 to operate, which connects the battery 12 with the winding of magnet 20. The energization of magnet 20 causes the line relay 21 to operate, which connects the battery 12 with the winding of magnet 23. The energization of magnet 23 causes the signal device 24 to operate, which causes the printer mechanism at station A to print the letter "A".

pleted. This circuit extends from the battery 12 through the armature and normal contact of relay 3, winding of magnet 6, segment 9, brush 8, and segment 10 of the distributor to ground. The electromagnet 6, in operating, withdraws the holding pawl 7 from engagement with the arm 5 and permits the same to be revolved with the shaft 14. The passage of the brush 8 over the various segments, and the operation of relay 3, in accordance with the selecting units for connecting the battery 12 with the ring 11, establishes an energizing circuit for certain of the relays 16 to 20, while relay 21 is energized over a local circuit completed through the segments of the distributor by the contact brush 8. It is therefore required, in order to complete the energizing circuit for magnet 23, that these relays be operated in a certain prescribed manner.

The passage of the brush 8 over the segments of the distributor, which are individual to each of the relays 16 to 20, causes the application of battery to the winding of these relays in accordance with the energization of the line relay 3, which, as previously pointed out, controls the application of the source of battery 12 with the ring 11 of the distributor. Thus, when the brush 8 is passing over a particular segment, and should relay 3 be operated at that instant, 120 125 130

the source of battery 12 will be connected with the relay which has its winding connected with this particular segment of the distributor. Inasmuch as the cam 15 is mounted on the same shaft as the arm 5, and has its recessed portion so arranged with respect to contact member 22, as to effect the closure of this contact just prior to the passage of brush 8 over the first segment of the distributor to which relays 16 to 21 inclusive are connected, ground will thereupon be applied to the winding of each of these relays. Thus when the source of battery 12 is connected with the ring 11 of the distributor, the relay connected with the segment over which the brush 8 is at that instant passing, will be energized. This circuit may be traced from battery 12, armature and alternate contact of relay 3, ring 11 of distributor 4, contact brush 8, a segment of the distributor 4, arm of switch 13, winding of the relay connected with the particular segment over which the brush 8 is passing, and contact 22 to ground. The transmission of the remaining selecting units, as previously noted, causes the energization of relays 16, 18 and 19. The passage of the brush 8 over the segment to which the winding of relay 21 is connected completes the energizing circuit for relay 21. A locking circuit for these relays is established upon their energization. This circuit extends from battery, through the right-hand contact and winding of these relays and contact 22 to ground, and will be maintained until the arm 5 has nearly completed its cycle, at which time the contact member 22 is caused to drop into the recess on the surface of the cam 15, thereby removing the ground connection. The energization of relays 16, 18, 19 and 21 completes a circuit including the winding of magnet 23, extending from battery through the left-hand contacts of relays 16 to 21 inclusive and the winding of magnet 23 to ground. It is thus seen from the above that each time the distributor arm is released, relay 21 will be energized as its energization is in no ways dependent upon the energization of relay 3. Unless this is the case, the energizing circuit for relay 23 will not be completed even though the other relays, previously enumerated, have been energized. Relay 23, in operating, attracts its armature and moves the arm 24 into engagement with the threaded member 26, which thereby causes a movement of this member away from its stop bar under the tension of a retractile spring. If the set of selecting units for operating relays 16, 18, 19 and 21 is transmitted over the line a definite number of times, and the time intervening between the set of selecting units making up the combination is not such as to allow the slow-release relay 23 to become deenergized, the member 24 will be moved so as to engage contact member 25. The engagement of this contact member 25 by the arm 24, completes a circuit including the signaling device 27, thereby causing its operation. The attendant upon receiving this signal is at once aware that the switch 13 should be thrown so as to connect the selecting magnets of the printer mechanism with the segments of the distributor 11 for the reception of a message. This having been done, the message can be transmitted in the usual manner.

The invention has been shown as applied to a start-stop system of printing telegraphy, but it is obvious that its application is not limited to this particular class of systems, as it may be employed in connection with a number of other systems without departing from the spirit and scope of the invention.

What is claimed is:

1. In combination with a signaling conductor having a plurality of stations connected thereto, of signal responsive means at each of the stations comprising a motor-driven distributor, contact control means rotated in synchronism with said distributor, a plurality of relays energized in accordance with current impulses allotted thereto by said distributor, a signaling device, and a slow-release relay controlled by the energization of said relays in predetermined combinations and the actuation of said contact control means to effect the operation of said signaling device.
2. The combination with a signaling conductor having a plurality of stations connected thereto, of a signal responsive means at each of the stations comprising an intermittently rotating distributor, a plurality of relays energized in accordance with current impulses allotted by said distributor, contact control means, a signaling device, and means controlled by the conjoint action of said contact control means and said relays when energized in a predetermined combination for causing the operation of said relay to effect the actuation of the signaling device.
3. In combination with a signaling conductor having a plurality of stations connected thereto, of signal responsive apparatus at each of the stations comprising a rotary distributor, a cam operated in synchronism with said distributor, circuit-controlling contacts associated with said cam, a slow-release relay, a plurality of relays energized in response to predetermined combinations of current impulses for causing the energization of said slow-release relay, a locking circuit for said relays completed upon the closing of said circuit control contacts by said cam, and a signaling device operated upon the energization of said slow-release relay for a definite period of time.

4. A signaling system comprising a line, a group of relays energized due to the transmission of current impulses over said line, a contact arm, a revolving member, a signaling device, and means operated upon the energization of certain ones of said relays for bringing said contact arm into engagement with the revolving member whereby said contact arm is advanced to cause the 10 operation of said signaling device.
5. A signaling system comprising a line, a plurality of relays energized due to the transmission of current impulses over said line, a signaling device, an electromagnet 15 operated upon the energization of certain ones of said relays, a revolving member, and a contact arm brought into engagement with said revolving member and advanced thereby upon the continued operation of said 20 magnet for operating said signaling device.
6. A signaling system comprising a line, a plurality of relays energized due to the transmission of current impulses over said line, a signaling device, an electromagnet 25 operated upon the energization of certain ones of said relays, a revolving member, and a contact arm brought into engagement with said revolving member and advanced thereby upon the continued operation of said 30 magnet a definite period of time for operating said signaling device.
7. A printing telegraph system comprising a line, a plurality of relays, a distributor for allotting current impulses as transmitted over said line to operate said relays, a slow-release relay energized upon the operation of said relays due to the transmission of a combination of impulses, and a signaling device operated upon the continued 40 operation of said slow-release relay.
8. A signaling system comprising a line, a plurality of relays, a distributor for allotting current impulses as transmitted over said line to operate said relays, a cam, a locking circuit for each of said relays controlled by said cam and established upon the operation of said relays, a slow-release relay energized upon the operation of said relays due to the transmission of a particular 45 combination of impulses, and a signaling device operated upon the continued operation of said slow-release relay.
9. A signaling system comprising a line, a plurality of stations on said line, a code signal for each of said stations, means operated in response to the transmission of said code signal, means operated upon the operation of said means, and a signaling device controlled by said last-mentioned means and operated only due to the repeated transmission of said code signal.
10. A signaling system comprising a line, a plurality of stations on said line, a distributor for allotting current impulses as transmitted over said line to said plurality 65 of stations, a code signal individual to each of said stations, a plurality of relays energized upon the transmission of said code signal, a slow-release relay energized upon the operation of said relays, and a signaling device controlled by said slow-release relay and operated upon the transmission of said code signal a definite number of times.
11. In combination with a printer mechanism, a line, a plurality of relays, a distributor, a switch controlling the connection of said printer mechanism and said relays with said distributor, a signaling device, and means operated due to the energization of certain ones of said relays and rendered 75 effective only upon the successive reenergization of such relays a definite number of times for causing the operation of said signaling device.
12. A signaling system comprising a line, a group of relays energized due to the transmission of current impulses over said line, a contact arm, a revolving member, means operated upon the energization of certain ones of said relays for bringing said contact arm into engagement with the revolving member whereby said contact arm is advanced horizontally, and a signaling device operated upon the advancement of said arm through a predetermined distance.
13. A signaling system comprising a line, a group of relays energized due to the transmission of current impulses over said line, a contact arm, a revolving member, means operated upon the energization of certain ones of said relays for bringing said contact arm into engagement with the revolving member whereby said contact arm is advanced, an electrically operating signaling device, and circuit connections controlled by said contact arm for causing the operation of the signaling device.
14. A signaling system comprising a line, a group of relays energized due to the transmission of current impulses over said line, a circuit closing device, a revolving member, means operated upon the energization of certain ones of said relays for bringing said circuit closing device into engagement with the revolving member for causing the movement thereof, and a signaling device controlled by said circuit closing device.

In witness whereof, I hereunto subscribe my name this 16th day of April, A. D. 1920.

JOHN H. BELL.
